PORTABLE PITCHER'S MOUND

John J. Goeders, 705 2nd Ave. SE,
Altoona, Iowa 50009

Filed Aug. 7, 1968, Ser. No. 13,050

Term of patent 14 years

Int. Cl. D21—03

U.S. Cl. D34—5

Fig. 1

Fig. 2

Fig. 3

Fig. 4

Fig. 5

I claim:

The ornamental design for a portable pitcher's mound, substantially as shown.
